COLLECTOR'S STAMP

George J. Matt, Brooklyn, N. Y., assignor to
 Roberts Numbering Machine Company, New
 York, N. Y., a corporation of New York

Application April 21, 1934, Serial No. 721,701

16 Claims. (Cl. 101—90)

The invention relates to a collector's stamp, and more particularly to a portable machine for making, simultaneously, a plurality of records of each transaction in which the machine is used, 5 through movement of the printing characters by means of a spring, the control of which is by a manually operative mechanism.

A machine of the type to which the invention relates is used for the purpose of impressing upon 10 the record book of a debtor, and upon a record strip, within the machine inaccessible to the collector, full data as to the time and amount of collection, with identification markings indicating the debtor and the collector. By the use of 15 the machine of the invention, the data upon the record strip must conform to that upon the debtor's record book, and alteration of the entries upon this record strip, or a failure to make entries thereon is prevented.

20 The various mechanisms in the machine must be so constructed and arranged as to be contained within sufficiently small bulk to make the stamp conveniently portable, and at the same time avoid any delicate or complicated mechanisms which are apt to break or get out of adjustment in a manner to interfere with the continued operativeness of the machine to an extent to prevent them making of proper records, either upon the debtor's record book or upon the concealed record strip.

The invention contemplates the use of a reciprocatory frame carrying a plurality of independently revoluble indicia wheels having printing characters thereon, which frame is rapidly moved when making an impression, by a compression spring of fairly high tension so as to ensure a staccato blow of the printing characters upon the record strip and carbon strips associated therewith, thus ensuring a clean sharp impression of the data indicated by the printing wheels upon the debtor's record book, and a duplication of this data upon the record strip within the machine. Manually operative means are provided in the machine for imparting movement to the reciprocatory frame away from the record strip, which means includes therein structural characteristics by which the parts operative upon said frame will be so held as to hold the tension of the spring and prevent the accidental application of the energy of the spring to the reciprocatory frame.

Each of the indicia wheels is provided with cameo or typo printing characters spaced in relation to each other, and within the recesses between these printing characters are non-print-

ing characters duplicating printing characters on the wheel and so spaced therefrom as to indicate through a suitable sight opening, the setting of the other or printing character of the pair when in the printing position. These wheels are manually turned, the absence of ink saturated fabric strips preventing the fouling of the wheels in a manner to interfere with the turning thereof by the hand without the aid of an instrument of any kind, or to soil the hand.

It is essential, in a machine embodying the invention, that means be provided for advancing the record strip and its associated carbon strips following the making of each impression, and that this means be automatically actuated as a result of movement of the frame carrying the indicia wheels.

To facilitate the threading of the record and associated strips through the machine, I provide a removable guide member which may be mounted in the machine after the reels of record and associated carbon strips are in place. I also provide means firmly holding the supply roll in position during the threading operation, which means are utilized to develop sufficient braking action upon said supply reel, during the feeding movement of the strips, to avoid such overrunning thereof during the feeding of the strips as might create excessive slack and develop wrinkling of the carbon strips in a manner to interfere with the sharpness of the impression made therethrough.

The invention consists primarily in a collector's stamp embodying therein a lower casing having an opening through the bottom thereof, supply and rewind reels upon opposite sides of said opening, a plurality of superimposed strips of record and carbon paper passing from said supply to said rewind reel with a carbon coated surface presented towards said opening, guides for said strips, an upper casing having a sight opening therethrough, closing said lower casing, movable therefrom, and having therein a guide bracket having vertical ways, a reciprocatory frame, a shaft carried thereby having its opposite ends mounted in said ways, a plurality of wheels idly mounted on said shaft, and projecting through said sight opening, each having a plurality of duplicated printing and non-printing characters so positioned that when a printing character is at the opening in the lower casing, the duplicate non-printing character is at said sight opening, a spring adapted to force said reciprocatory frame toward said lower casing, and manually operative means acting upon said frame

to move it away from said opening, tension said spring, hold said frame against movement by said spring, and release said frame to permit said spring to operate thereon, and co-operating means carried by said rewind reel and said reciprocatory frame, whereby said strips will be advanced with each upward movement of said frame; and in such other novel features of construction and combination of parts as are herein-
5 after set forth and described, and more particularly pointed out in the claims hereto appended.

Referring to the drawing,

Fig. 1 is a front elevation of a collector's stamp embodying the invention with the casing broken 10 away to disclose operative mechanisms of the machine;

Fig. 2 is a section on the line 2—2 of Fig. 1;

Fig. 3 is a top plan view of the lower casing showing the manner of mounting the composite 15 printing and recording strips in the machine; and

Fig. 4 is a detail view of the mechanisms controlling the spring energy for actuating the machine.

25 Like numerals refer to like parts throughout the several views.

In the embodiment of the invention shown in the drawing, I employ a dished lower casing 10 having an opening 11 through the bottom 30 thereof. Within this casing are side bars 12, each having bearing saddles 13 and 14 for a supply reel 15 of a record and associated carbon strips, the upper carbon strip being shown at 16, the record strip at 17 and the lower carbon strip at 18, and a rewind reel at 19. The coated surface of the strip 16 is engaged with the record strip 17, and the coated surface of the carbon surface 18 is presented toward the opening 11.

The lower casing 10 is supported from a base 40 plate 20 by means of a side bar 21 and screws passing therethrough and through one of the side bars 12, as shown in Fig. 3 of the drawing. The other side bar 12 is secured to the side wall of the lower casing by means of screws, or in any other desired manner. Portions of the bars 12 are extended, as shown at 22, and pass through slots formed in the front and rear walls of the lower casing.

The base 20, adjacent the side bars 21, is of 50 greater thickness than other parts thereof, forming a gauge for positioning a record book in relation to the printing line and spacing the bottom of the lower casing 10 from the base 20 to an extent to form a space or slot 23 for the reception 55 of said book.

Loosely mounted in the base 20 are a plurality of presser or clamp plungers 24 freely movable toward and from the bottom of the lower casing 10, so that when a book is properly positioned, 60 it will be held against displacement by merely placing the stamp upon a flat object. This is to avoid shifting of the book while the machine is actuated, in a manner to be more fully described hereinafter. These plungers are positioned upon opposite sides of the opening 11.

Inset in the base 20, along the longitudinal center of the opening 11, is a soft platen 25 to ensure the making of a clean impression with the actuation of the machine upon the record book, 70 and also upon the record sheet. This platen is desirable although not necessary.

It is essential that the principal shall have access to the record strip, and desirable that the collector shall not have access thereto. This 75 record strip is used by the principal, not only in

checking up the amount of the collections and the accounts to which these collections are to be applied, but to enable the making of entries in the proper accounts in order that the office books may accord with the debtor's record book, and to determine the failure to make payments when due.

To prevent access to the record strip by a collector while permitting the free access thereto by one authorized to consult the record strip, I 10 provide a top casing 26 closing the lower casing 10 and supporting the various mechanisms utilized in impressing the data as to each transaction, and for feeding the record and its associated carbon strips through the machine.

15 Said casing 26 has a sight opening 27 in the front wall thereof and carries a U-shaped bracket 28 carrying plates 29 having vertical guideways 30 therein and base extensions 31 coinciding in length with the side bars 12 and having upper bearing saddles 32 registering with the saddles 13 and 14 respectively. The side bars 12 have a circular stop recess 33 therein aligned with the guideways 30.

20 Mounted within the bracket 28 is a vertically reciprocatory U-frame 34 carrying a shaft 35 on which are idly mounted, side by side, a plurality of indicia wheels 36.

25 Each of the indicia wheels 36 has a plurality of printing characters 37, spaced apart by depressions in which are indicated duplicate characters 38 of those appearing upon the printing surfaces. The printing characters 37 are cameo or typo, while the non-printing characters 38 are preferably in intaglio so that the lines may be filled with suitable coloring matter to enable the user of the machine by observation of the non-printing characters through the sight opening 27 to visualize the setting of the other or printing character of the pair of duplicate characters.

30 In the drawing, the various indicia wheels have twelve printing characters about the perimeter thereof, and there are also twelve non-printing characters. The printing character of one pair is spaced substantially 120° from the non-printing character of the pair so that when any printing character is above the opening 11, the corresponding non-printing character will be positioned at the sight opening 27.

35 Associated with each indicia wheel 36 is a ratchet wheel 39, the number of teeth of which will correspond with the number of printing characters. Associated with each ratchet wheel is a 40 detent pawl 40, the teeth of the ratchet wheel and the detent pawl being so positioned as to be operatively engaged, one with the other, when a printing character is in its printing position above the opening 11. In setting the various indicia wheels, said wheels are moved step by step so that as each printing character and an adjacent non-printing character occupy 30° in arc of the wheel, the movement of the wheel must be 30° with each step, thus preventing the accidental locating of a non-printing character in the printing position instead of a printing character.

45 Passing across the U-frame 34 are two bars 41 and 42, the detent pawls 40 being pivoted upon the bar 41 and the bar 42 being engaged by a curved portion 43 of a comb spring 44, the teeth of which respectively engage the detent pawls associated with the different indicia wheels. Said comb spring 44 is provided with a looped portion 45 passing between and engaging the bar 42 and the heels of the respective pawls 40. One tooth of the comb spring does not engage a de-

tent pawl, but is utilized in connection with the operation of the strip feeding mechanism in a manner to be more fully referred to hereinafter.

Surmounting the U-frame 34 is a second upwardly directed U-frame 46 having adjacent the top thereof, a shaft 47, upon the opposite ends of which anti-friction rollers 48 are mounted. This U-frame 46 is provided with vertical guide openings 49 in the opposite legs thereof. Passing through said guide opening and through the legs of the U-frame 28 is a rotatable shaft 50 forming a part of the mechanism by which the actuation of the indicia wheels is manually controlled. Carried by the U-frame 28 is a stud 51 co-operating with which is a sleeve 52 carried by the U-frame 46. The stud 51 and the sleeve 52 have telescopic relation one to the other and about both of these parts is a heavy coiled spring 53 for developing energy utilized in imparting a rapid movement to the U-frames 34 and 46 and the various parts carried thereby, so as to cause the printing operation to be by a staccato blow upon the strips 16, 17 and 18 and therethrough upon the debtor's record book positioned in the slot 23.

The shaft 50, adjacent each end thereof, is provided with a cam 54 having a gradual rise 55 and an abrupt fall 56. Intermediate the rise and fall is a depression 57. Each cam 54 co-operates with an anti-friction roller 48 and has associated therewith a segmental ratchet wheel 58. Co-operating with said ratchet wheel is a spring pressed detent pawl 59. A segmental ratchet pawl is used to permit return movement of the cams in the event that the operator imparts excessive movement thereto when raising the indicia wheels and tensioning spring 53. The pawl 59 is pivoted upon the U-bracket 28.

Carried by the shaft 50 is a crank 60, the hand-hold portion 61 of which is pivotally supported so as to permit the turning of the crank in a manner to engage said hand-hold with openings 62 in one leg of the bracket 28 and in the casing 26 so as to lock said shaft against accidental movement when the machine is not in use.

The strip feeding mechanism includes therein a ratchet wheel 63 carried by the rewind reel 19, a spring pressed detent pawl 64 mounted in the lower casing 10 and co-operating with said ratchet wheel, and means carried by the U-frame 34 engageable with said ratchet wheel upon the downward movement of said frame to impart turning movement thereto upon the upward movement thereof. This means comprises a pawl 65 pivoted upon the frame 34 and having a cam surface 66 which, by engagement with the ratchet wheel 63, oscillates said pawl so as to bring the tooth 67 of the pawl into engaging relation with the ratchet wheel 63. The cam surface 66 is also adapted to engage the teeth of said ratchet wheel in the event of overrunning of the rewind reel or of any leg in the spring acting upon the actuating pawl 65. The pawl 65 is pivoted upon the rod 41 and has an angular arm 68 acted upon by one of the teeth of the comb spring 44, as shown more particularly in Fig. 2 of the drawing.

In threading the composite strips 16, 17 and 18 through the machine, and to hold the portion thereof between the reels 15 and 19 closely adjacent the bottom of the lower casing 10, I provide guide rods 69 and 70 extending across said casing from side to side thereof above and closely adjacent the opening 11 and upon opposite sides of the printing line.

To avoid the inconvenience of passing the strips below these guide rods when threading the

strips through the machine, I preferably provide these rods with end plates 71 having a snug fit with the side bars 12 of the lower casing, each end plate having a plurality of outwardly extending lugs 72 seated in notches in the top of said side bars.

The plates 71 project across the curved portion 33 and are recessed to register with these openings, as shown at 73. In this manner, the frame composed of the guide rods 69 and 70 and the end plates 71 is removable from the casing to facilitate the mounting of a composite strip in, or its removal from, the lower casing 10.

Each side bar 12, adjacent the bearing saddle 13 therein, has secured thereto a forked spring clip 74 for holding the supply reel 15 upon said bearing when the machine is open, to permit a convenient mounting of the arbors of said reel in, and their removal from, the bearing saddles, and to offer sufficient resistance to the turning movement of the reel during the feeding of the strips to prevent excessive creation of slack as a result of overrunning of the reel.

The top casing 26 is hinged to the lower casing 10 by means of hinge members 75 pivoted to one end of the side bars 12 of the lower casing.

The two casings may be locked in relation to each other by means of any suitable locking mechanism 76, a conventional snap lock being shown in the drawing.

The shaft 35, movable in the guideways 30, and the shaft 50, movable in the guide openings 49, ensure a right line movement to the indicia wheels with the actuation of the machine.

The manner of use of the herein described stamp, and its mode of operation is substantially as follows:—

A collector is furnished with a list of debtors, the amount to be collected from each, and all other information necessary to enable him to properly record collections from each debtor. The record and carbon strips 16, 17 and 18 upon a supply reel 15 are mounted in the bearing saddles 13, and the free end thereof secured to said reel in any desired manner, as by means of a slot passing through the rewind reel 19. The frame carrying the guide rods 69—70 is removed from the lower casing 10 during this attachment of the strips to the rewind reel and until said rewind reel has been positioned in the bearing saddles 13.

When the reel is so positioned, the detent pawl 64 prevents clockwise rotation of the rewind reel, so that when the frame, including said guide rods 69—70, is replaced in said lower casing, the supply reel 15 only will be turned so as to bring the composite strip closely adjacent the bottom of the lower casing as a result of the forcing of said guide bars and the end plates 71 thereof into position within said casing. The top casing 26 is then closed upon, and locked in relation to, the lower casing 10.

Before mounting the said strips in the lower casing, the shaft 50 is turned by means of the crank 60 to an extent to permit the anti-friction rollers 48 to enter the depressions 57 in the cams 54. With the parts in this position, the U-frames 34 and 46 are raised against the tension of the spring 53, upward movement of said frames increasing the tension of said spring 70 which is normally under tension.

The depressions 57 prevent the energy of the spring from imparting turning movement to the cams 54 in a manner to permit the descent of the frames 34 and 46. To guard against acci-

dental rotation of the shaft 50, the hand-hold portion of the crank 60 is turned downwardly and the hand-hold 61 passed through the openings 62.

5 When collecting money from a debtor, the collector inserts the debtor's record book in the slot
23 between the base 20 and the bottom of the lower casing 10. The shoulder formed by the thick portion of said base serves to accurately
10 gauge the position of the book to ensure the various items set upon the indicia wheels appearing in their proper position laterally of the book, side gauge markings upon the outer wall of the lower casing being used to accurately locate the
15 line of the book upon which the record is to be made. When a book is once properly positioned, the collector sets the stamp upon any flat object, the weight of the stamp forcing the plungers 24 inwardly so as to firmly hold the book in
20 its adjusted position.

20 its adjusted position.
Before inserting the book in the slot 23, the collector rotates the various indicia wheels 36 to bring the various printing characters 37 into printing position. Said wheels are turned by hand, and the non-printing characters 38, as a result of the turning of the wheels, are exposed through the sight opening 27 in the top casing 26, so that by merely observing these characters the collector may determine the setting of the 20 printing characters 37.

30 printing characters 31. When the wheels necessary to indicate the desired data have been properly set, and the debtor's record book has been properly positioned in the manner above described, the collector 35 merely disengages the hand-hold 61 from the openings 62, and turns the shaft 50 until the rise 55 of the cams passes out of engagement with the anti-friction rollers 48, thus permitting the expansion of the spring 53 in a manner to 40 impart a swift downward movement to the frames 34 and 46 to an extent to engage the printing characters upon the wheels 36 with the strip 16 with a staccato blow.

45 The rapid downward movement of the indicia wheels, and the force of the blow resulting from the expansion of the spring 53 make, through the carbon strip 16, a sharp impression of the printing characters upon the record strip 17, and the carbon strip 18 makes a sharp impression, a duplicate of that upon the carbon strip, upon the debtor's record book. The record strip 17 between the carbon strips 16 and 18 prevents puncturing of the carbon strips as a result of the force of the blow from the printing characters. The tension of the spring 53 is sufficiently great to prevent any rebound of the indicia wheels or the U-frames carrying same.

50

55

With downward movement of the U-frame 34, the feeding pawl 65 is forced to the right, Fig. 2, as it rides over the teeth of the ratchet wheel 63, this movement of said pawl being against the tension of the tooth of the comb spring 44 acting upon the angular extension 68. During this movement, the detent pawl 64 prevents clockwise movement of the rewind reel 19 in a manner to create slack in the said strips to an extent which might result in the formation of wrinkles in the carbon strips. Such wrinkles result in an imperfect impression.

70 After the actuation of the stamp in the manner above described by the expansion of the spring 53, it is necessary for the collector to again turn the shaft 50, during which movement the rise 55 of the cams 54 will impart upward movement to the U-frames 34 and 46, during

75

the initial part of which upward movement the feeding pawl 65 turns the rewind reel 19 to an extent to advance the various strips so as to secure a proper spacing between succeeding impressions upon the record strip 17. Upon the initial upward movement of the indicia wheels 36 and before there has been any substantial movement of the rewind reel, said indicia wheels are disengaged from the strip 16 so as to permit the free run of the strips 16, 17 and 18 without likelihood of tearing said strip 16. 10

The fall 56 of the cams 54 affords clearance for the downward movement of the rollers 48, and the recesses 57 in the cams 54 define the extent of movement required of the cams to properly tension the spring 53 and prevent the accidental operation of the machine by excess movement of the shaft 50. As the tension of the spring 53 is increased as a result of the upward movement of the reciprocatory printing unit, the pawl 59 engages the ratchet wheel 58 preventing the actuation of the machine in the event that the user accidentally loses control of the actuating crank. 15 20

The crank 60 has clockwise movement only, 25
the pawl and ratchet mechanism 58 and 59 pre-
venting contra-clockwise movement of this hand-
hold when the indicia wheels are in the print-
ing position.

During the feeding movement of the strips, 30 the spring clips 74 acting upon the arbors of the supply reel 15 offer sufficient resistance to the turning movement of said wheel to ensure the clips being held taut in their run across the opening 11 in the bottom of the casing 10. With 35 downward movement of the indicia wheels, following their initial engagement with the strip 16, the strips 16, 17 and 18 will be forced through the opening 11 into engagement with the debtor's record book, during which downward movement 40 the reel 15 has slight turning movement to create the necessary slack to permit this movement of the strips. Subsequent actuation of the re-wind reel will take up this slack and impart further turning movement to the supply reel. 45

When a stamp is returned to the possession of the principal, the record strip 17 will have impressed thereon full data as to each collection made, thus not only checking the money returns of the collector, but affording a record by which proper entries may be made in the accounts of the several debtors to indicate the status of their account at all times. It is impossible for a collector to apply funds received from one debtor to the account of another debtor, since the data upon the record strip will indicate not only the collections which were made, but the collections which were not made, the latter being indicated by the absence of any record upon the strip corresponding with the lists from which the collector worked. 50 55 60

While it is desirable to prevent access by the collector to the interior of the stamp, this is not necessary since such access will not permit any alterations in the entries upon the record strip 17, since the superimposing of one impression upon another will merely make the record illegible, or sufficiently so to require explanation. 65

With the ordinary functioning of the stamp, the record strip 17 must be fed after the making of each impression and cannot be fed without the making of an impression. The number of collections made during a day and the length of the composite record strip 16, 17 and 18 precludes all possibility of the destruction of records

already made and the re-making of false records. In fact, the machine of the invention offers a safeguard against an improper return of money, a temporary misapplication of funds, or an improper application of collections in the manner above described. The machine cannot prevent theft of collected funds, but will ensure an immediate detection of any defalcation.

The use of indicia wheels idly mounted upon a shaft carried by a reciprocatory frame having a right line movement toward and from the surfaces upon which matter is to be impressed, and the exposure of a portion of the perimeter of these wheels through a sight opening in the top casing, not only increases the range of the variation of the records which may be impressed, but permits the use of wheels of small diameter and avoids necessity for additional mechanisms for turning the wheels or indicating the setting thereof.

While it is preferable to employ three strips 16, 17 and 18 in the manner described, it is possible to use only two strips each of which is carbon coated, the lower one of which includes heavy weight coated paper sufficiently strong to avoid likelihood of the tearing of the strip and afford a suitable surface upon which a record may be impressed by an upper thin strip of carbon coated paper. By using three separate strips, it is possible to use the strips of carbon paper a number of times by reassembling these strips in relation to a record strip after removal of the latter for making book entries therefrom.

A single spring 53, located midway of the width of the U-frames 34 and 46, has been found to give satisfactory results. The telescoping stud 51 and sleeve 52, in addition to aiding in guiding the movements of the printing unit, also serve to prevent displacement of the spring in a manner to interfere with a proper operation of the stamp.

The use of ratchet wheels 39 and their co-operating detent pawls 40 constructed as described prevents not only the accidental turning of the indicia wheels after they have been set to record the desired data, but overturning of the wheels during the setting thereof in a manner to cause the making of an imperfect and illegible impression.

It is not my intention to limit the invention to the precise details of construction shown in the accompanying drawing, it being apparent that such may be varied without departing from the spirit and scope of the invention.

Having described the invention, what I claim as new and desire to have protected by Letters Patent, is:—

1. A collector's stamp embodying therein a lower casing having an opening through the bottom thereof, supply and rewind reels upon opposite sides of said opening, a plurality of superimposed strips of record and carbon paper passing from said supply to said rewind reel with a carbon coated surface presented towards said opening, guides for said strips, an upper casing having a sight opening therethrough, closing said lower casing, movable therefrom, and having therein a guide bracket having vertical ways, a reciprocatory frame, a shaft carried thereby having its opposite ends mounted in said ways, a plurality of wheels idly mounted on said shaft, and projecting through said sight opening, each having a plurality of duplicated printing and non-printing characters so positioned that when a printing character is at the opening in the lower casing, the duplicate non-printing character is at said sight opening, a spring adapted to force said reciprocatory frame toward said lower casing, and manually operative means acting upon said frame to move it away from said opening, tension said spring, hold said frame against movement by said spring, and release said frame to permit said spring to operate thereon, and co-operating means carried by said rewind reel and said reciprocatory frame, whereby said strips will be advanced with each upward movement of said frame.

is at said sight opening, a spring adapted to force said reciprocatory frame toward said lower casing, and manually operative means acting upon said frame to move it away from said opening, tension said spring, hold said frame against movement by said spring, and release said frame to permit said spring to operate thereon, and co-operating means carried by said rewind reel and said reciprocatory frame, whereby said strips will be advanced with each upward movement of said frame.

2. A collector's stamp embodying therein a lower casing having an opening through the bottom thereof, and side bars having bearing saddles adjacent the opposite ends thereof, supply and rewind reels removably mounted in said saddles, a plurality of superimposed strips of record and carbon paper passing from said supply to said rewind reel with a carbon coated surface presented towards said opening, guides for said strips, an upper casing having a sight opening therethrough, closing said lower casing, movable therefrom, and having therein a guide bracket having vertical ways, having extensions provided with bearing saddles co-operating with the saddles in said side bars, a reciprocatory frame, a shaft carried thereby having its opposite ends mounted in said ways, a plurality of wheels idly mounted on said shaft, and projecting through said sight opening, each having a plurality of duplicated printing and non-printing characters so positioned that when a printing character is at the opening in the lower casing, the duplicate non-printing character is at said sight opening, a spring adapted to force said reciprocatory frame toward said lower casing, and manually operative means acting upon said frame to move it away from said opening, tension said spring, hold said frame against movement by said spring, and release said frame to permit said spring to operate thereon, and co-operating means carried by said rewind reel and said reciprocatory frame, whereby said strips will be advanced with each upward movement of said frame.

3. A collector's stamp embodying therein a platen base, a lower casing having an opening through the bottom thereof, supported by, and spaced from said base, supply and rewind reels upon opposite sides of said opening, a plurality of superimposed strips of record and carbon paper passing from said supply to said rewind reel with a carbon coated surface presented towards said opening, guides for said strips, an upper casing having a sight opening therethrough, closing said lower casing, movable therefrom, and having therein a guide bracket having vertical ways, a reciprocatory frame, a shaft carried thereby having its opposite ends mounted in said ways, a plurality of wheels idly mounted on said shaft, and projecting through said sight opening, each having a plurality of duplicated printing and non-printing characters so positioned that when a printing character is at the opening in the lower casing, the duplicate non-printing character is at said sight opening, a spring adapted to force said reciprocatory frame toward said lower casing, and manually operative means acting upon said frame to move it away from said opening, tension said spring, hold said frame against movement by said spring, and release said frame to permit said spring to operate thereon, and co-operating means carried by said rewind reel and said reciprocatory frame, whereby said strips will be advanced with each upward movement of said frame.

4. A collector's stamp embodying therein a platen base, a lower casing having an opening through the bottom thereof, supported by, and spaced from said base, plungers movably mounted in, and projecting from the bottom of said base, supply and rewind reels upon opposite sides of said opening, a plurality of superimposed strips of record and carbon paper passing from said supply to said rewind reel with a carbon coated surface presented towards said opening, guides for said strips, an upper casing having a sight opening therethrough, closing said lower casing, movable therefrom, and having therein a guide bracket having vertical ways, a reciprocatory frame, a shaft carried thereby having its opposite ends mounted in said ways, a plurality of wheels idly mounted on said shaft, and projecting through said sight opening, each having a plurality of duplicated printing and non-printing characters so positioned that when a printing character is at the opening in the lower casing, the duplicate non-printing character is at said sight opening, a spring adapted to force said reciprocatory frame toward said lower casing, and manually operative means acting upon said frame to move it away from said opening, tension said spring, hold said frame against movement by said spring, and release said frame to permit said spring to operate thereon, and cooperating means carried by said rewind reel and said reciprocatory frame, whereby said strips will be advanced with each upward movement of said frame.

frame.
5. A collector's stamp embodying therein a
lower casing having an opening through the bot-
tom thereof, supply and rewind reels upon oppo-
site sides of said opening, a plurality of super-
imposed strips of record and carbon paper pass-
ing from said supply to said rewind reel with a
40 carbon coated surface presented towards said
opening, guides for said strips, an upper casing
having a sight opening therethrough, closing said
lower casing, movable therefrom, and having
therein a guide bracket having vertical ways, a
45 reciprocatory frame, a shaft carried thereby hav-
ing its opposite ends mounted in said ways, a
plurality of wheels idly mounted on said shaft,
and projecting through said sight opening, each
having a plurality of duplicated printing and
50 non-printing characters so positioned that when
a printing character is at the opening in the
lower casing, the duplicate non-printing charac-
ter is at said sight opening, a spring adapted to
force said reciprocatory frame toward said lower
55 casing, a rotatable shaft, a cam having a gradual
rise and an abrupt fall, a hand crank upon said
shaft, means upon said frame engageable by said
cam, and co-operating means carried by said
rewind reel and said reciprocatory frame, where-
60 by said strips will be advanced with each upward
movement of said frame.

6. A collector's stamp embodying therein a lower casing having an opening through the bottom thereof, supply and rewind reels upon opposite sides of said opening, a plurality of superimposed strips of record and carbon paper passing from said supply to said rewind reel with a carbon coated surface presented towards said opening, guides for said strips, an upper casing 65 having a sight opening therethrough, closing said lower casing, movable therefrom, and having therein a guide bracket having vertical ways, a reciprocatory frame, a shaft carried thereby having its opposite ends mounted in said ways, a 70 plurality of wheels idly mounted on said shaft, 75

and projecting through said sight opening, each having a plurality of duplicated printing and non-printing characters so positioned that when a printing character is at the opening in the lower casing, the duplicate non-printing character is at said sight opening, a stud carried by said top casing, a sleeve telescoping with said stud carried by said frame, a spring encircling said stud and said sleeve, a rotatable shaft, a cam having a gradual rise and an abrupt fall, a hand crank upon said shaft, means upon said frame engageable by said cam, and co-operating means carried by said rewind reel and said reciprocatory frame, whereby said strips will be advanced with each upward movement of said frame.

7. A collector's stamp embodying therein a lower casing having an opening through the bottom thereof, supply and rewind reels upon opposite sides of said opening, a plurality of superimposed strips of record and carbon paper passing from said supply to said rewind reel with a carbon coated surface presented towards said opening, guides for said strips, an upper casing having a sight opening therethrough, closing said lower casing, movable therefrom, and having therein a guide bracket having vertical ways, a reciprocatory frame, a shaft carried thereby having its opposite ends mounted in said ways, a plurality of wheels idly mounted on said shaft, and projecting through said sight opening, each having a plurality of duplicated printing and non-printing characters so positioned that when a printing character is at the opening in the lower casing, the duplicate non-printing character is at said sight opening, a stud carried by said top casing, a sleeve telescoping with said stud carried by said frame, a spring encircling said stud and said sleeve, a rotatable shaft, a cam having a gradual rise and an abrupt fall, a hand crank upon said shaft, means upon said frame engageable by said cam, said cam adjacent its fall having a notch therein to prevent action of the spring turning said cam, and co-operating means carried by said rewind reel and said reciprocatory frame, whereby said strips will be advanced with each upward movement of said frame. 43

8. A collector's stamp embodying therein a lower casing having an opening through the bottom thereof, supply and rewind reels upon opposite sides of said opening, a plurality of superimposed strips of record and carbon paper passing from said supply to said rewind reel with a carbon coated surface presented towards said opening, guides for said strips, an upper casing having a sight opening therethrough, closing said lower casing, movable therefrom, and having therein a guide bracket having vertical ways, a reciprocatory frame, a shaft carried thereby having its opposite ends mounted in said ways, a plurality of wheels idly mounted on said shaft, and projecting through said sight opening, each having a plurality of duplicated printing and non-printing characters so positioned that when a printing character is at the opening in the lower casing, the duplicate non-printing character is at said sight opening, a U-frame carried by said reciprocatory frame, having upwardly directed legs having guide slots therein, a compression spring between said U-frame and said top casing, a rotatable shaft carried by said casing and passing through said guide slots, a cam having a gradual rise and an abrupt fall upon said shaft, a hand crank upon said shaft, means upon said frame engageable by said cam, and co-operating means carried by said rewind reel and said 50 55 60 65 70 75

reciprocatory frame, whereby said strips will be advanced with each upward movement of said frame.

9. A collector's stamp embodying therein a platen base, a lower casing having an opening through the bottom thereof, supported by, and spaced from said base, supply and rewind reels upon opposite sides of said opening, a plurality of superimposed strips of record and carbon paper passing from said supply to said rewind reel with a carbon coated surface presented towards said opening, guides for said strips, an upper casing having a sight opening therethrough, closing said lower casing, movable therefrom, and having therein a guide bracket having vertical ways, a reciprocatory frame, a shaft carried thereby having its opposite ends mounted in said ways, a plurality of wheels idly mounted on said shaft, and projecting through said sight opening, each having a plurality of duplicated printing and non-printing characters so positioned that when a printing character is at the opening in the lower casing, the duplicate non-printing character is at said sight opening, a U-frame carried by said reciprocatory frame, having upwardly directed legs having guide slots therein, a stud carried by said top casing, a sleeve telescoping with said stud carried by said U-frame, a spring encircling said stud and said sleeve, a rotatable shaft passing through said guide slots, a cam having a gradual rise and an abrupt fall, a hand crank upon said shaft, means upon said U-frame engageable by said cam, and co-operating means carried by said rewind reel and said reciprocatory frame, whereby said strips will be advanced with each upward movement of said frame.

10. A collector's stamp embodying therein a lower casing having an opening through the bottom thereof, supply and rewind reels upon opposite sides of said opening, a retard device operative upon said supply reel, a plurality of superimposed strips of record and carbon paper passing from said supply to said rewind reel with a carbon coated surface presented towards said opening, guides for said strips, an upper casing having a sight opening therethrough, closing said lower casing, movable therefrom, and having therein a guide bracket having vertical ways, a reciprocatory frame, a shaft carried thereby having its opposite ends mounted in said ways, a plurality of wheels idly mounted on said shaft, and projecting through said sight opening, each having a plurality of duplicated printing and non-printing characters so positioned that when a printing character is at the opening in the lower casing, the duplicate non-printing character is at said sight opening, a spring adapted to force said reciprocatory frame toward said lower casing, and manually operative means acting upon said frame to move it away from said opening, tension said spring, hold said frame against movement by said spring, and release said frame to permit said spring to operate thereon, and co-operating means carried by said rewind reel and said reciprocatory frame, whereby said strips will be advanced with each upward movement of said frame.

11. A collector's stamp embodying therein a lower casing having an opening through the bottom thereof, and side bars having bearing saddles adjacent the opposite ends thereof, supply and rewind reels removably mounted in said saddles, a spring yoke carried by a side bar adjacent said saddle and engageable with said supply reel, a plurality of superimposed strips of record and

carbon paper passing from said supply to said rewind reel with a carbon coated surface presented towards said opening, guides for said strips, an upper casing having a sight opening therethrough, closing said lower casing, movable therefrom, and having therein a guide bracket having vertical ways, and having extensions provided with bearing saddles co-operating with the saddles in said side bars, a reciprocatory frame, a shaft carried thereby having its opposite ends mounted in said ways, a plurality of wheels idly mounted on said shaft, and projecting through said sight opening, each having a plurality of duplicated printing and non-printing characters so positioned that when a printing character is at the opening in the lower casing, the duplicate non-printing character is at said sight opening, a spring adapted to force said reciprocatory frame toward said lower casing, and manually operative means acting upon said frame to move it away from said opening, tension said spring, hold said frame against movement by said spring, and release said frame to permit said spring to operate thereon, and co-operating means carried by said rewind reel and said reciprocatory frame, whereby said strips will be advanced with each upward movement of said frame.

12. A collector's stamp embodying therein a lower casing having an opening through the bottom thereof, supply and rewind reels upon opposite sides of said opening, a plurality of superimposed strips of record and carbon paper passing from said supply to said rewind reel with a carbon coated surface presented towards said opening, guides for said strips, an upper casing having a sight opening therethrough, hingedly connected with said lower casing at one side of the opening through the bottom thereof, closing said lower casing, movable therefrom, and having therein a guide bracket having vertical ways, a reciprocatory frame, a shaft carried thereby having its opposite ends mounted in said ways, a plurality of wheels idly mounted on said shaft, and projecting through said sight opening, each having a plurality of duplicated printing and non-printing characters so positioned that when a printing character is at the opening in the lower casing, the duplicate non-printing character is at said sight opening, a spring adapted to force said reciprocatory frame toward said lower casing, and manually operative means acting upon said frame to move it away from said opening, tension said spring, hold said frame against movement by said spring, and release said frame to permit said spring to operate thereon, and co-operating means carried by said rewind reel and said reciprocatory frame, whereby said strips will be advanced with each upward movement of said frame.

13. A collector's stamp embodying therein a lower casing having an opening through the bottom thereof, supply and rewind reels upon opposite sides of said opening, a plurality of superimposed strips of record and carbon paper passing from said supply to said rewind reel with a carbon coated surface presented towards said opening, guides for said strips, an upper casing having a sight opening therethrough, closing said lower casing, movable therefrom, and having therein a guide bracket having vertical ways, a reciprocatory frame, a shaft carried thereby having its opposite ends mounted in said ways, a plurality of wheels idly mounted on said shaft, and projecting through said sight opening, each having a plurality of duplicated printing and non-

printing characters so positioned that when a printing character is at the opening in the lower casing, the duplicate non-printing character is at said sight opening, a spring adapted to force 5 said reciprocatory frame toward said lower casing and manually operative means acting upon said frame to move it away from said opening, tension said spring, hold said frame against movement by said spring, and release said frame to permit said spring to operate thereon, a ratchet 10 wheel carried by each of said other wheels, having teeth corresponding in number with the printing characters thereon, a spring pressed detent pawl co-operating with each ratchet wheel, and co-operating means carried by said rewind 15 reel and said reciprocatory frame, whereby said strips will be advanced with each upward movement of said frame.

14. A collector's stamp embodying therein a lower casing having an opening through the bottom thereof, and side bars having bearing saddles adjacent the opposite ends thereof, supply and rewind reels removably mounted in said saddles, a plurality of superimposed strips of record and carbon paper passing from said supply to said 20 rewind reel with a carbon coated surface presented towards said opening, guides for said strips, an upper casing having a sight opening therethrough, closing said lower casing, movable therefrom, and having therein a guide bracket having vertical 25 ways, and having extensions provided with bearing saddles co-operating with the saddles in said side bars, a reciprocatory frame, a shaft carried thereby having its opposite ends mounted in said ways, a plurality of wheels idly mounted on said 30 shaft, and projecting through said sight opening, each having a plurality of duplicated printing and non-printing characters so positioned that when a printing character is at the opening in the lower casing, the duplicate non-printing character is at said sight opening, a spring adapted to force 35 said reciprocatory frame toward said lower casing, and manually operative means acting upon said frame to move it away from said opening, tension said spring, hold said frame against movement by said spring, and release said frame to permit said spring to operate thereon, a ratchet wheel carried by said rewind reel, and a spring 40 pressed pawl pivotally mounted upon, and movable with, said frame, said pawl being normally disengaged from said ratchet wheel, but engageable therewith upon the depression of said frame, whereby said rewind reel will be actuated with the upward movement of said frame.

15. A collector's stamp embodying therein a lower casing having an opening through the bottom thereof, supply and rewind reels upon opposite sides of said opening, a plurality of superimposed strips of record and carbon paper passing from said supply to said rewind reel with a carbon coated surface presented towards said opening, guides for said strips, an upper casing 45 having a sight opening therethrough, closing said lower casing, movable therefrom, and having therein a guide bracket having vertical ways, and having extensions provided with bearing saddles co-operating with the saddles in said side bars, a reciprocatory frame, a shaft carried thereby having its opposite ends mounted in said ways, a plurality of 50 wheels idly mounted on said shaft, and projecting through said sight opening, each having a plurality of duplicated printing and non-printing characters so positioned that when a printing character is at the opening in the lower casing, the duplicate non-printing character is at said sight opening, a spring adapted to force said reciprocatory frame toward said lower casing, and manually operative means acting upon said frame to move it away from said opening, tension said spring, hold said frame against movement by said spring, and release said frame to permit said spring to operate thereon, and co-operating means carried by said rewind reel and said reciprocatory frame, whereby said strips will be advanced with each upward movement of said frame.

having a sight opening therethrough, closing said lower casing, movable therefrom, and having therein a guide bracket having vertical ways, a reciprocatory frame, a shaft carried thereby having its opposite ends mounted in said ways, a plurality of wheels idly mounted on said shaft, and projecting through said sight opening, each having a plurality of duplicated printing and non-printing characters so positioned that when a printing character is at the opening in the lower casing, the duplicate non-printing character is at said sight opening, a spring adapted to force said reciprocatory frame toward said lower casing, and manually operative means acting upon said frame to move it away from said opening, tension said spring, hold said frame against movement by said spring, and release said frame to permit said spring to operate thereon, a ratchet wheel carried by said rewind reel, and a spring 10 pressed pawl pivotally mounted upon, and movable with, said frame, said pawl being normally disengaged from said ratchet wheel, but engageable therewith upon the depression of said frame, whereby said rewind reel will be actuated with the upward movement of said frame.

16. A collector's stamp embodying therein a lower casing having an opening through the bottom thereof, and side bars having bearing saddles adjacent the opposite ends thereof, supply and rewind reels removably mounted in said saddles, a plurality of superimposed strips of record and carbon paper passing from said supply to said rewind reel with a carbon coated surface presented towards said opening, a frame having end plates, having a close sliding fit with said side bars respectively, and guide rods extending between said plates adjacent the opening in said lower casing, an upper casing having a sight opening therethrough, closing said lower casing, movable therefrom, and having therein a guide bracket having vertical ways, and having extensions provided with bearing saddles co-operating with the saddles in said side bars, a reciprocatory frame, a shaft carried thereby having its opposite ends mounted in said ways, a plurality of 35 wheels idly mounted on said shaft, and projecting through said sight opening, each having a plurality of duplicated printing and non-printing characters so positioned that when a printing character is at the opening in the lower casing, the duplicate non-printing character is at said sight opening, a spring adapted to force said reciprocatory frame toward said lower casing, and manually operative means acting upon said frame to move it away from said opening, tension said spring, hold said frame against movement by said spring, and release said frame to permit said spring to operate thereon, and co-operating means carried by said rewind reel and said reciprocatory frame, whereby said strips will be advanced with each upward movement of said frame.

GEORGE J. MATT.
